UNITED STATES PATENT OFFICE.

ROBERT W. GORMLY, OF TROY, NEW YORK.

BUR-WHEEL.

SPECIFICATION forming part of Letters Patent No. 778,857, dated January 3, 1905.

Application filed October 24, 1903. Serial No. 178,328.

To all whom it may concern

Be it known that I, ROBERT W. GORMLY, a citizen of the United States, residing at Troy, county of Rensselaer, and State of New York, have invented certain new and useful Improvements in Bur-Wheels, of which the following is a specification.

The invention relates to such improvements; and it consists of the novel construction and combination of parts hereinafter described and subsequently claimed.

Reference may be had to the accompanying drawings and the reference characters marked thereon, which form a part of this specification.

Similar characters refer to similar parts in the several figures.

Figure 1 of the drawings is a view in side elevation of my improved bur-wheel. Fig. 2 is a diametrical section of the same. Fig. 3 is a transverse section of the same, partly broken away, the section being taken on the broken line 3 3 in Fig. 1. Fig. 4 is a plan view of one of the blades detached. Fig. 5 is a plan view of one of the presser-blocks detached. Fig. 6 is a side view of the presser-block shown in Fig. 5. Fig. 7 is a plan view of the inner side of the grooved washer or clamping-plate. Fig. 8 is a central cross-section of the same. Fig. 9 is a plan view of the grooved end of the hub.

The invention relates to bur-wheels used in feeding yarn to the needles of a circular-knitting machine, and more particularly to bur-wheels in which it is desired to fill or partially fill the needle-spaces between certain blades in the wheel.

Certain objects of the invention are to more positively secure the blades in the wheel and to provide a more durable support for the presser-blocks used in such a wheel.

Other objects of the invention will appear in connection with the following description.

Referring to the drawings, wherein the invention is shown in its preferred form, 5 is the hub of the wheel, which is preferably made of brass or similar easily-workable metal, said hub being provided with oblique slots 6, adapted to contain the wings or blades 7, which are secured in their slots by means

of an annular clamping-plate or washer 8, which presses upon the shanks of the blades and holds the beveled part 9 of each blade in an annular end groove 10, formed in the hub, the clamping-plate being forced against the shanks of the blades by means of the bearing-sleeve or bushing 12, which passes through central apertures in the hub and clamping-plate and is provided on one end with a head or flange 14, adapted to bear upon said plate, 60 and on its other end with the screw-threaded portion 15, adapted to receive a clamping-nut 16.

The construction as above described is substantially the same as that shown and described in the Kavanaugh patent, No. 117,299, dated July 25, 1871, to which patent reference may be had for a more complete understanding of such construction.

It is well known to those skilled in the art of knitting that it is desirable in making certain kinds of goods to omit the knitting of a stitch by certain of the needles during certain rotations of the knitting-cylinder. This has been accomplished by filling or partly filling the needle-space between two blades of the bur-wheel used in feeding the yarn to the needles with a block, which may be termed a "presser-block." The manner of operation of such wheels and presser-blocks is well understood 80 in the art and need not be particularly described in this specification.

The blade-receiving slots 6 in the hub occupy planes radial to the center of the hub, though arranged obliquely to its axial line, 85 for which reason the spaces between the blades inserted in the oblique slots taper toward the center of the hub. For this reason the presser-blocks 25, which are inserted between certain of the blades, are made thicker at their outer 90 needle-engaging edge 21 than at their inner attaching edge, tapering to correspond with the needle-spaces, so that the blocks will approximately fill said spaces when inserted therein, as shown in Fig. 3. As a means for securing the blocks in the spaces between the blades the blocks are severally provided on their inner edge with an attaching-shank 22, adapted to enter the circumferential groove 23 in the hub, which is cut deeper than the oblique slots, 100

and the attaching-shank is provided with an offset or hook 24, adapted to pass behind the inner edge of a neighboring blade and engage therewith to prevent the removal of the block, 5 as shown in Fig. 3. The attaching-shank may be a little wider than the groove, because it extends obliquely or diagonally across the groove. The blades may be inserted in the hub in the usual manner, and while the blades 10 are being inserted the required needle-spaces are severally filled with a block, which is placed against the last-inserted blade with its shank in the groove 23 and its hook 24 extending behind said blade, and a blade is inserted in 15 the next oblique slot, which prevents the block from being disengaged without removing a blade. After all the oblique slots are filled with blades and the desired number of needle-spaces filled with blocks, as aforesaid, the 20 clamping-plate 8 is forced into engagement with the shanks of the blades by means of the flanged bushing 12 and nut 16.

One feature of my invention consists in providing the several blades on the end opposite 25 the shank 9 with a tongue or lip 1, having a beveled surface 2, which lip or tongue is adapted to project beyond the end of the hub opposite the end provided with the groove 10 and fit a correspondingly-formed annular groove 30 4 in the inner face of a clamping-plate or washer 3, interposed between the nut 16 and the neighboring end of the hub. When the nut 16 is tightened, all the blades are confined between the two clamping-plates or washers 35 3 and 8, which, in connection with the hub, serve to positively support and lock the opposite ends of the blades against displacement. As heretofore constructed wheels of the Kavanaugh type have been provided with means 40 for locking the blades only at their shank ends, leaving their other ends unlocked and free to yield to pressure tending to force them out of the oblique slots.

Another feature of my invention consists in 45 extending the presser-blocks at their opposite ends beyond the ends of the hub into engagement with the peripheral surfaces of the washers 3 and 8, as shown in Fig. 1. These washers or clamping-plates are made of relatively 50 hard material, as hardened steel, well adapted to withstand the wearing action of the blocks thereupon due to the thrust of the needles against the blocks in use, and it is thus possible to entirely relieve the hub from such 55 wearing action of the blocks, permitting the hub to be made of relatively soft material, such as brass, which can easily be worked into the desired shape and provided with the oblique slots to receive the blades.

60 For certain purposes of my invention the presser-blocks may be secured in the wheel in any known manner, and means other than that shown may be employed for locking the blades in position.

My invention is applicable to various kinds 65 of bur-wheels for use in knitting-machines.

From an inspection of Fig. 2 it will be seen that the pressure of the washer 3 is transmitted to the hub 5 through the presser-blocks 25 and their shanks, thereby enabling said 70 hub to resist the pressure of the washer 8 in clamping between said washer 8 and the hub the shanks 9 of the blades, which are thereby locked in position independently of the nibs 1 and groove 4. Should the presser-blocks be 75 omitted, the washer 3 can be sprung sufficiently at its central portion and forced inwardly thereat into engagement with the hub by means of the nut 16 to afford the necessary resistance to the clamping action of the washer 8. 80

What I claim as new, and desire to secure by Letters Patent, is—

1. In a bur-wheel, the combination with a hub of relatively soft material provided with a series of slots in its periphery; and a series of 85 blades secured in said slots; of a washer of relatively hard material secured adjacent to an end of the hub; and a presser-block secured between two neighboring blades extending beyond the hub into engagement with said 90 washer.

2. In a bur-wheel, the combination with a hub of relatively soft material provided with a series of slots in its periphery; and a series of 95 blades secured in said slots; of a pair of washers of relatively hard material secured adjacent to the opposite ends of the hub; and a presser-block secured between two neighboring blades extending at its opposite ends beyond the hub into engagement with said washers respectively. 100

3. In a bur-wheel, the combination with a hub of relatively soft material provided with a series of slots and a circumferential groove in 105 its peripheral portion; of a series of blades secured in said slots; a pair of washers of relatively hard material secured adjacent to the opposite ends of the hub; and a presser-block interposed between two neighboring blades, said block having a shank inserted and secured in the circumferential groove in the hub and having its opposite ends extended beyond the hub into engagement with said washers respectively. 110

4. In a bur-wheel, the combination with a 115 hub of relatively soft material provided with a series of slots and a circumferential groove in its peripheral portion; of a series of blades secured in said slots; a pair of washers of relatively hard material secured adjacent to the 120 opposite ends of the hub; and a presser-block interposed between two neighboring blades, said block having a shank inserted in said circumferential groove in the hub and on said shank a hook engageable with a neighboring 125 blade, the opposite ends of the block being extended beyond the hub into engagement with said washers respectively.

5. In a bur-wheel, the combination with a hub provided with a series of slots in its periphery and in one end with an annular groove; of a series of blades inserted in said slots each having at one end a shank projecting beyond the grooved end of the hub and located in said groove, and at its other end a tongue projecting beyond the other end of the hub; a washer adjacent to the grooved end of the hub engageable with the projecting shanks of the blades; a washer adjacent to the other end of the hub provided with an annular groove adapted to receive the projecting tongues of the blades; and means for forcing the washers toward each other to clamp the interposed blades therebetween and their shanks between the hub and shank-engaging washer.

6. In a bur-wheel, the combination with a hub of relatively soft material provided with a series of slots in its periphery and in one end with an annular groove; of a series of blades inserted in said slots each having at one end

a shank projecting beyond the grooved end of the hub and located in said groove, and at its other end a tongue projecting beyond the other end of the hub; a washer of relatively hard material adjacent to the grooved end of the hub engageable with the projecting shanks of the blades; a washer of relatively hard material adjacent to the other end of the hub provided with an annular groove adapted to receive the projecting tongues of the blades; means for forcing the washers toward each other to clamp therebetween the interposed blades; and a presser-block secured between two neighboring blades extending beyond the hub at its opposite ends into engagement with said washers respectively.

In testimony whereof I have hereunto set my hand this 21st day of October, 1903.

ROBERT W. GORMLY.
